UNITED STATES PATENT OFFICE.

EDWIN C. McFARLANE, OF BROOKLYN, NEW YORK, ASSIGNOR TO SPECIAL STAMPING AND MANUFACTURING CORP., OF NEW YORK, N. Y., A CORPORATION OF NEW YORK.

BEDPOST LOCK.

Application filed January 7, 1925. Serial No. 991.

To all whom it may concern:

Be it known that I, EDWIN C. McFARLANE, a citizen of the United States, residing at No. 355 East 51st Street, borough of Brooklyn, county of Kings, State of New York, (whose post-office address is 203 Lafayette Street, borough of Manhattan, city of New York, State of New York), have invented a new and useful Bedpost Lock, of which the following is a full, clear, and exact description.

My invention relates to a bedpost lock of the wedge type, and the object thereof is to provide a lock of the type referred to, which is simple and rigid in construction and which can be manufactured economically.

I attain this object by the construction illustrated in the accompanying drawing in which—

Figure 1 is a top plan view of a bedpost provided with an embodiment of my invention;

Figure 2 is a vertical section on a line 2—2, Figure 1;

Figure 3 is a perspective view of the wedge carrying plate;

Figure 4 is a perspective view of the bedpost bracket into which the wedge of the plate fits; and

Figure 5 is an elevation of the wedge carrying plate from the wedge side thereof.

Referring to the drawing, 10 is a tubular bedpost to which a post bracket 11 is connected by means of rivets 12. Preferably the side 13 of the bracket which contacts with the bedpost is curved in conformity with the post 10. The tube at the bracket is reinforced by a liner 14, so that the rivets 12 will connect the bracket 11 rigidly to the bedpost 10. The side 15 of the bracket which extends from the post has a tapering slot 16, open at the top, as best shown in Figures 1, 2 and 4.

A wedge 17 fits into the slot 16. The wedge is partially sheered out from a plate 18 and bent or pressed to one side of that plate so that when the wedge 17 engages the slot 16, the plate 18 contacts with the adjacent face of the side 15 of the bracket 11. The plate 18 has an arm 19 extending

laterally of the wedge, and the arm is offset toward the wedge so that the arm and the wedge are lying substantially in a common plane. The wedge and the arm 55 have apertures 20 and 21 respectively, so that the wedge plate 18 could be secured by means of rivets 22 and 23 to angle iron 24 forming part of the bed frame.

As it will be seen, the wedge 17 and the arm 19 are off-set to the extent equivalent to the thickness of the side 15 of the bracket 11. When the wedge plate 18 is secured to the angle iron 24, as shown in Figures 1 and 2, they both, that is, the angle iron and the plate 18, firmly embrace the side 15 of the bracket 11 when the wedge 17 is engaged into the slot of the bracket.

When holes 20 are punched in the wedge 17, the sides of the wedge at the holes are 70 slightly bulged, as best shown in Figure 5 and indicated as bosses 25. It is self-evident that the punching of the holes 20 to obtain the bosses 25 on the sides of the wedge must be done after the sheering and bending of 75 the wedge 17 out of the plate 18. By providing these bosses 25 on the side of the edges, I am able to obtain a better fit of the wedge 17 in the groove 16; as all the work of this type is generally done on a punch press and is somewhat rough, and a good contact between the sides of the slot 16 and the sides of the wedge would be difficult to obtain, a few predetermined points of contact are selected beforehand and those are 80 85 the bosses 25.

I claim:

A bedpost lock comprising a bracket adapted to be secured to the post and having a portion thereof extending from the post, said extended portion of the bracket having a tapered slot, a plate having a wedge to one side thereof for engaging the slot, and an arm extending from the plate and offset to the same side as the wedge, 90 said wedge having bosses on the sides thereof for better engaging the sides of the slot, and said wedge and arm having means for securing thereto an angle iron of a bed frame.

EDWIN C. McFARLANE.
